US0D1040413S

(12) **United States Design Patent** (10) Patent No.: **US D1,040,413 S**
(45) Date of Patent: **** Aug. 27, 2024**

(54) **FLOODLIGHT PROJECTOR**

(71) Applicant: **ROXX GmbH**, Cologne (DE)

(72) Inventor: **Marco Hoersch**, Hamburg (DE)

(73) Assignee: **ROXX GMBH**, Cologne (DE)

(**) Term: **15 Years**

(21) Appl. No.: **29/837,847**

(22) Filed: **May 9, 2022**

(30) **Foreign Application Priority Data**

Nov. 18, 2021 (EM) 008763247-0001

(51) **LOC (14) Cl.** **26-05**

(52) **U.S. Cl.**

USPC **D26/63**; D26/72

(58) **Field of Classification Search**

USPC D16/203, 209; D26/24, 37, 44, 46, 61, D26/63, 72, 79, 80, 81, 84, 86, 85, D26/88-90, 93, 104-108, 110, 112, 113, D26/118, 122-124, 128-130

CPC F21L 4/027; F21S 8/00; F21S 8/02; F21S 8/04; F21S 8/046

(57) **CLAIM**

The ornamental design for floodlight projector, as shown and described.

DESCRIPTION

FIG. 1 is a perspective view of a floodlight projector; and, FIG. 2 is a top elevational view thereof.

The broken lines shown in the drawings illustrate portions of the article and form no part of the claimed design.

1 Claim, 2 Drawing Sheets
